Inventor:
Joseph Ingersoll,

By *James T. Berkley*,
his attorney.

UNITED STATES PATENT OFFICE.

JOSEPH INGERSOLL, OF LOS ANGELES, CALIFORNIA, ASSIGNOR TO JAMES B. PATTERSON, OF LOS ANGELES, CALIFORNIA.

LADDER CONSTRUCTION.

Application filed April 17, 1922, Serial No. 554,026. Renewed December 15, 1926.

The present invention relates to ladder construction, and has to do particularly with improvements in means for securing the steps to the side rails or stiles without mortising the latter.

Specifically it pertains to improved means for detachably securing the steps to the stiles, so that the steps may be replaced, as they become worn, with a minimum effort and expense; at the same time providing a rigid and durable construction having few parts.

The foremost object of the invention is strength of construction combined with simplicity. These features are characterized by the use of a metallic joint-forming member, formed of a single piece of material; wherein riveting is eliminated and a minimum number of bolts used; so that the parts may be easily and quickly assembled or replaced. Also the joint forming members are so formed that the bolt heads will engage with metal parts and not with the wooden steps or stiles.

The invention will be more fully set forth in the following specification, reference being made therein to the accompanying drawings forming a part thereof in which drawings:

Figure 1 is a plan view illustrating the configuration of the blank from which the joint forming member is formed. Figure 2 is a section showing the manner of attaching the member to the steps and stiles, and Fig. 3 is a bottom plan view thereof.

While my invention will be hereinafter described in its application to step-ladder construction—where it will undoubtedly have its greatest utility—it will nevertheless be clear that it may be applied to many other similar constructions, where steps may be secured to side rails.

Referring now particularly to Fig. 2 the numeral 10 designates the side rail or stile of a typical step ladder, and 11 one of a plurality of steps secured therebetween at the usual intervals.

My improved joint forming member is designated generally by the numeral 15; which is formed of a single piece of suitable material, such as galvanized iron. These members are made in rights and lefts, identical except for their formation for such reversed

positions. A blank from which they are formed is illustrated in Fig. 1, and in plan is of a cruciform configuration. It consists of a central body portion from which arms 16 extend laterally and arms 17 and 18 extend at substantially right angles to the arms 16. The arms 16 are tapered towards their outer ends, terminating in rounded ends 16^a to present a finished appearance; in which ends bolt holes 19 are punched. Similarly the arm 17 is tapered towards its outer end, terminating in a rounded end 17^a, and having a bolt hole 20 punched therein. The arm 17 is somewhat shorter than the arms 16, as illustrated. The arm 18 is somewhat longer than the arm 17, having parallel sides 21 extending part of its length, which terminate in a tapered portion and rounded end 18^a, a bolt hole 22 being likewise punched in the latter. An aperture 23^a is punched in the arm 18 slightly inward of its outer tapered end, as shown in Fig. 1.

After thus forming the joint forming member, from a single piece of material, the arms 16 and 17 are bent to extend in opposite directions and at substantially right angles to the plane of the body portion, being bent along the dotted lines shown at 16^b and 17^b, 80 of Fig. 1. The arm 18, hereinafter termed the brace arm, is then bent in the same direction as the arm 17, along the dotted line 18^b; but instead of extending at substantially right angles to the plane of the body portion it extends upwardly at an angle thereto and towards the arm 17; after which its outer tapered end 18^a is bent downwardly to extend outwardly in a plane parallel with the plane of the arm 17, after its being bent 90 over as just described.

When the blank is first formed a portion 24 is stamped out so that it may be bent outwardly in the same direction as the arm 17, along a line 24^a, to form a flange, spaced from 95 and parallel with the plane of the arm 17, after its being bent as described. A bolt hole 25 is also punched in the body portion, situated immediately below the flange 24.

After being thus formed, the member is 100 ready for attachment to the stile and step of the ladder, as illustrated in the other figures of the drawings, being clearly illustrated in Fig. 2. This I prefer to do by first se-

curing the member to the step 11 by extending the end of the step between the arm 17 and the parallel bent over portion 18^a of the brace arm 18, inserting it therein until its transverse end 11^a abuts against the inner face of the body portion. It may be here noted that the flange 24 is so positioned that it will extend inwardly from the body portion in a plane with the bent over portion 18^a of the arm 18, as clearly shown in Fig. 2. Thus the step 11 is supported upon the flange 24 and the brace arm 18. The bolt holes 20 and 22 in the arms 17 and 18, respectively, are so positioned that when the arms 17 and 18 are bent, as hereinbefore described, these holes will be coaxial, through which a bolt 26 may be extended and also through a registering aperture 27 in the step 11. The bolt 26 is thus extended downwardly through the arm 17, step 11, and arm portion 18^a so that its top 26^a (which will be preferably rounded) will engage the arm 17 and so a nut 28 may be attached to its opposite end from the under side of the step 11.

25 After thus securing the member to the step 11, both may then be secured to one of the stiles 10 by resting the body portion against the inner face of the stile and then bending the arms 16 around the longitudinal edges of the stile and inwardly towards each other across its opposite or outer face, bringing them together tightly around the stile so the bolt holes 19 will register with each other.

35 After thus overlapping the arms 16 a tie bolt 29 is extended through the registering apertures 19, an aperture 31 in the stile 10, the aperture 25 in the body portion and the aperture 23^a in the brace arm 18 and a nut 32 applied to its outer end.

40 A reinforcing plate 33, formed of comparatively heavy material, is provided, angularly bent, as shown, to conform to the configuration of the under-face of the brace arm 18, and having apertures 34 and 35 positioned to register with the apertures 22 and 23^a of the arm 18.

45 The hole 23^a is positioned centrally of the brace arm 18 and only large enough to receive the tie bolt 29^a; the latter being bent over adjacent its head 29^b so that it may extend through the registering holes 23^a and 35 at substantially right angles to the brace arm 18 and plate 33. The head 29^b flatly engages the plate, and the shank of the bolt extends through the hole 31.

50 The step bolt 27 extends through the registering holes 22 and 34, in the arm portion 18^a and plate 33 respectively, and receives the nut 28, which is screwed up tightly against the plate 33, to clamp it and the brace arm end 18^a tightly against the under face of the step 11.

55 Thus the plate 33 forms a rigid connection between the bolts 26 and 29^a, so that, in

effect, they not only rigidly tie the step to the stile but form a substantial support for the step. The plate 33 is used so that the joint forming member 15 may be constructed of a light and easily handled material, yet reinforced at the point of greatest strain. Without the plate 33 such material would not be strong enough to stand the strain produced by the bolts 27 and 29^a.

60 While I have herein shown and described the preferred specific embodiment of my invention, I nevertheless reserve the right to make such modifications or changes in structure which will properly come within the scope of the appended claims. As, for instance, I may utilize only my particular arrangement of bolts for securing the parts together; or I may use them in combination with metallic plates fashioned to aid in supporting and bracing the parts, as described, without departing from the spirit of my invention.

Having described a preferred form of my invention I claim:

1. In a step-ladder construction or the like the combination with a step and stile of a joint forming device comprising a metal plate having a body portion adapted to engage the inner face of the stile; arms extending laterally from said body portion to embrace the longitudinal edges of the stile and lap across its outer face; an arm extending inwardly from the top of said body portion to engage the top face of the step; an arm extending inwardly from said body portion to engage the bottom face of the step; a securing bolt extending transversely through said step and its engaging arms; a securing bolt extending transversely through said stile and its overlapped embracing arms and said body portion; and a reinforcing plate connecting the adjacent ends of said bolts; the said arms serving to space the ends of said bolts from the stile and step.

2. In a step-ladder construction or the like, the combination with a step and stile, of a joint forming device comprising a metal plate having a body portion adapted to engage the inner face of the stile; arms extending laterally from said body portion to embrace the longitudinal edges of the stile and lap across its outer face; an arm extending inwardly from the top of said body portion to engage the top face of the step; a brace arm extending inwardly and upwardly from the bottom edge of said body portion, the upper end of said brace arm being bent to lie flat against the under face of the step; a securing bolt extending transversely through said step and its engaging arms; a securing bolt extending transversely through said stile, its overlapped embracing arms, said body portion and the diagonal portion of the brace arm;

and a reinforcing plate conforming to the contour of the outer face of the brace arm held against said brace arm by said bolts extending therethrough, said plate forming 5 a rigid connection between the adjacent ends of said bolts, the head of the bolt extending through the stile being bent at an angle with

its shank to lie flat against the face of the reinforcing plate.

In witness that I claim the foregoing I 10 have hereunto subscribed my name this 27th day of Feb., 1922.

JOSEPH INGERSOLL.
